UNITED STATES PATENT OFFICE.

DAVID CHRISTOPHER BLACK, OF ALLOA, SCOTLAND, ASSIGNOR TO THE PARSONS
MARINE STEAM TURBINE COMPANY LIMITED, OF WALLSEND, ENGLAND.

SHIP-PROPULSION INSTALLATION.

1,336,019.

Specification of Letters Patent.

Patented Apr. 6, 1920.

Application filed January 19, 1918, Serial No. 212,746. Renewed December 31, 1919. Serial No. 243,544.

To all whom it may concern:

Be it known that I, DAVID CHRISTOPHER BLACK, a subject of the King of Great Britain and Ireland, and residing at 4 Bank street, Alloa, in the county of Clackmannan, Scotland, have invented certain new and useful Improvements in and Relating to Ship-Propulsion Installations, of which the following is a specification.

10 The present invention relates to ship propulsion installations of the type where one, two or more motors or sets of motors drive through gearing one, two or more propeller shafts.

15 In such installations where two or more propellers are used, the propeller shafts usually pass either through a large tunnel in the holds or through separate ones, the distance between the shafts in the engine room being approximately the same as that between the propellers, all the gearing being in the engine room, or in a recess adjacent to it. This arrangement compared with a single screw vessel involves loss of hold 25 space, broken stowage, increased weight and cost of structure of tunnels, etc., in a varying degree, depending upon the number of shafts and the arrangement, and it is a method of minimizing these objections which is the object of the present invention, as applied to 30 installations where two or more propellers are used.

The object of the present invention is to arrange the engines, intermediate shafts and 35 gearing of a geared ship propulsion installation in such a manner as to give the maximum hold space in the vessel and to minimize the hold space occupied by the power transmission system.

40 I have found that in installations for ship propulsion in which reduction gearing is employed, considerable economy of hold space may be obtained by a careful consideration of the disposition of the various 45 shafts and gearing by which power is transmitted from the turbines or other prime movers to the propellers.

The invention consists broadly in an improved arrangement of the transmission 50 gearing between the engine room and the propellers so arranged that the greatest possible economy of hold space is obtained without sacrifice of efficiency.

The invention further consists in an in-

stallation for ship propulsion in which single or multiple reduction gearing with the necessary intermediate shafts are so arranged that more than one intermediate shaft is employed in a single tunnel or in tunnels close together in the space between the engine room and the propellers, whereby a more convenient hold space is provided.

The invention further consists in an installation having single or multiple reduction gearing in which the intermediate shafts passing through the hold are spread farther apart than the propeller shafts and placed in separate tunnels disposed in the wings of the hold or in spaces provided outside the hold, *e. g.*, for anti-torpedo protection.

The invention further consists in an installation in which multiple reduction gearing is employed, the gearing being divided, one or more gears being situated in the proximity of the engine room and other gears being situated aft of the after hold, the intermediate shafts being so displaced relatively to the axes of the motor shafts and propeller shafts as to give a greater hold space.

The invention further consists in the improved installations for ship propulsion in which reduction gearing is employed hereinafter described.

In my invention I propose to place part or the whole of the gearing in some convenient position as far aft of the engine room as possible, so arranged in the case of two or more propellers as to bring adjacent intermediate shafts closer together, and, if desired, lower than their respective propeller shafts. This will enable two or more shafts to be accommodated in one tunnel and so reduce the number or size of the tunnels, or both, thus increasing the hold space, giving better stowage and reducing the weight and cost of the structure of the tunnels.

Alternatively the intermediate shafts may be spread farther apart and placed in separate tunnels disposed in the wings of the hold, so as to provide improved stowage, or in spaces provided outside the hold for anti-torpedo protection or other purposes.

The motors used may be turbine, electric, reciprocating, oil, gas or other well-known type and the gearing may be of single, dou-

ble or more reductions and may be mechanical, hydraulic or other well known type.

Referring to the accompanying drawings:—

Figure 1 is a plan showing a two-shaft installation construction according to the invention;

Fig. 2 shows a three-shaft arrangement;

Fig. 3 shows a four-shaft arrangement in which the intermediate shafts are grouped in pairs;

Fig. 4 shows a modified arrangement in which the intermediate shafts are grouped in pairs;

Fig. 5 shows a modification in which one of the intermediate shafts is hollow, the other shaft passing through it;

Fig. 6 shows a four-shaft modification, in which all the shafts pass through a single tunnel;

Fig. 7 shows a modification in which the intermediate shafts and gearing are arranged so as to give considerable width of hold space, the tunnels being placed in proximity to the sides of the vessel.

In the modification of the invention shown in Fig. 1, two intermediate shafts *a b* are provided in a single tunnel *c*. As illustrated, each intermediate shaft is driven through gearing *d d* by three turbines *1, 2, 3*. In this modification two propeller shafts *e f* are driven from the intermediate shafts through gearing *g h*; the reduction gearings *g h* in this case are so arranged that the intermediate shafts *a b* are closer together than the propeller shafts *e, f*, while the reduction gearings *g h* are placed as far aft as is convenient. The intermediate shafts pass through a single tunnel; or if more convenient, two tunnels very close together may be provided, as, for example, in the case where the hold is traversed by a longitudinal bulkhead, or fresh water tanks are arranged between the tunnels. The gears may be single or multiple.

In the modification shown in Fig. 2, three propeller shafts *l m n* are employed, the two outer propeller shafts *l n* being driven by single or multiple reduction gearing *o p* aft of the hold, while the central propeller shaft is provided with single or multiple gearing *q* only in the engine room. Turbines *r s* are directly coupled to the intermediate shafts *u w* driving the outer propellers and all three shafts *u v w* are situated in a single tunnel *x*. The turbines *r* and *s* may drive their shafts *u* and *w* respectively through gearing.

In the modification of the invention shown in Fig. 3, four propellers are employed driven by single or multiple reduction gearing *4, 5, 6, 7*, from four intermediate shafts *8, 9, 10, 11*, the intermediate shafts being situated in pairs in two tunnels *12, 13*, any

suitable arrangement of turbines with or without gearing being employed in the engine room to drive these four intermediate shafts.

In a modification of the invention shown in Fig. 4, single or multiple reduction gearings *14, 15* are provided on each of the inner intermediate shafts *16, 17*, the two outer shafts *18, 19*, running direct from the propellers to the engine room. In this case also the two outer pairs of shafts pass through two tunnels, *20, 21*, close to the sides of the ship.

In the form of the invention shown in Fig. 5 in which two propellers are employed, one intermediate shaft *40* is hollow and drives one of the propeller shafts *41* through a single or multiple reduction gearing *42*. The other intermediate shaft *43* runs inside the hollow shaft *40* and drives the other propeller shaft *44* through a reduction gearing *45*. The arrangement of the motors in the engine room according to this modification may be any suitable arrangement and forms no part of the present invention.

In the form of the invention shown in Fig. 6 none of the gearings are placed in the engine room and four intermediate shafts *22, 23, 24, 25*, are provided in a single tunnel *26*. The two inner shafts *23, 24* drive the propeller shafts *27, 28* through single or multiple reduction gearings *29, 30* while the outer intermediate shafts *22, 25*, drive the outer propeller shafts *31, 32* through single or multiple reduction gearings *33, 34*.

In the form of the invention shown in Fig. 7, the intermediate shafts *61, 62* are placed in tunnels *63, 64*, built against the sides of the ship. The reduction gearings are divided, the first reductions *65, 66* being placed in the engine room in such a position that the intermediate shafting is well outside the main portion of the engines and gearing. In some cases, however, the turbines may be placed in the wings and drive the after gearing direct. The second reductions *67, 68* are placed as far aft as convenient and are so arranged that the propeller shafting is considerably nearer the central line of the vessel than the intermediate shafting. In this manner a very considerable width of hold space is provided without any central tunnels for the shafting. The gears may be single or multiple.

It will be seen that the arrangements illustrated are only examples illustrating the principle of the invention, the essential features of which are the arrangement of the gearing relatively to the shafting in such a manner that the hold space is increased or rendered more convenient by utilizing the necessary displacement of shafts owing to the use of gearing in such a manner that the intermediate shafting passing along the length of the hold is

either arranged collectively in a less number of tunnels than would otherwise be required or so disposed relatively to the hull of the ship that a greater uninterrupted hold space 5 is available.

Further advantages of placing the whole or part of the gearing at some distance from the engine room are that the intermediate shafting is lighter as it runs at 10 a higher speed than the propeller shaft, and that the engine room itself can usually be made shorter than when all the gearing is placed in it, thus giving a further gain in hold capacity in addition to that obtained 15 from the smaller tunnels. If desired, automatic means can be used to indicate and prevent damage due to a failure of the oil supply or undue heating of the gears, thrusts and bearings when located aft.

With the intermediate shafts brought 20 close together as described in the foregoing arrangements—if there is a primary reduction in the engine room between these shafts and the motors—it may possibly be desirable 25 able to have one gear case of each pair of shafts arranged forward of its set of motors and the other arranged aft of its motors. This has the advantage that each power unit in the engine room for a pair of shafts 30 is of the same hand instead of being opposite hands as is usual, making the two sets of motors and gears identical. Such an arrangement is shown in Fig. 3.

Having now described my invention, what 35 I claim as new and desire to secure by Letters Patent is:—

1. In marine propulsion installations, a plurality of propeller shafts, driving means located in an engine room, shafts intermediate 40 the driving means and the propeller shafts, and extending along the hull of the vessel aft of the engine room, each of the said intermediate shafts being displaced axially out of line with the propeller shaft 45 it is to drive, tunnel means in which said shafts are located, and gearing between each aft end of the intermediate shafts and its propeller shaft, said gearing being spaced from the engine room and aft the hold, said 50 displaced intermediate shafts providing greater unbroken hold space.

2. In marine propulsion installations, a plurality of propeller shafts, driving means located in an engine room, shafts intermediate 55 the driving means and the propeller shafts, and extending along the hull of the vessel, each of the said intermediate shafts being displaced axially out of line with the propeller shaft it is to drive, tunnel means in 60 which said shafts are located, reduction gearing between the aft end of each intermediate shaft and its propeller shaft, and reduction gearing in the engine room between the driving means and the said intermediate 65 shafts, said gearings being widely separated

and said displaced intermediate shafts providing greater unbroken hold space.

3. In marine propulsion installations, a plurality of propeller shafts, driving means located in the engine room, shafts intermediate 70 the driving means and the propeller shafts, and extending along the hull of the vessel aft of the engine rooms, said intermediate shafts being spaced apart and lying close to the sides of the vessel, tunnels close 75 to the sides of the vessel in which said intermediate shafts are located, each of said intermediate shafts being displaced axially out of line with the propeller shaft it is to drive, and gearing between the aft ends 80 of the intermediate shafts and the propeller shafts, substantially as described.

4. In marine propulsion installation, a plurality of propeller shafts, driving means located in an engine room, shafts intermediate 85 the driving means and the propeller shafts, and extending along the hull of the vessel aft the engine room, each of the said intermediate shafts being displaced axially out of line with the propeller shaft it is to 90 drive, tunnel means in which said intermediate shafts are located and gearing between the aft end of each intermediate shaft and its propeller shaft, said gearing being widely spaced from the engine room and 95 aft the hold, said displaced intermediate shafts providing greater unbroken hold space, a plurality of said intermediate shafts being located in the same tunnel with the gearing belonging thereto extending in opposite 100 directions in relation to each other, substantially as described.

5. In marine propulsion installation, a plurality of propeller shafts, driving means located in an engine room, shafts intermediate 105 the driving means and the propeller shafts, and extending along the hull of the vessel aft the engine room, each of said intermediate shafts being displaced axially out of line with the propeller shaft it is to 110 drive, tunnel means in which said intermediate shafts are located and gearing between the aft end of each intermediate shaft and its propeller shaft, said gearing being widely spaced from the engine room and aft 115 the hold, said displaced intermediate shafts providing greater unbroken hold space, a plurality of said intermediate shafts being located in the same tunnel with the gearing belonging thereto extending in opposite directions in relation to each other, and said intermediate shafts being arranged side by side, substantially as described.

In testimony whereof I have signed my name to this specification.

DAVID CHRISTOPHER BLACK.
